LOCKING BICYCLE STAND

Gary D. Corkill, 1143 E. D St.,
Ontario, Calif. 91764

Filed Apr. 16, 1973, Ser. No. 351,377

Term of patent 14 years

Int. Cl. D8—99

U.S. Cl. D12—115

FIG. 1.

FIG. 2.

FIG. 3.

FIG. 1 is a perspective view of a locking bicycle stand showing my new design;

FIG. 2 is a side elevational view thereof opposite to that shown in FIG. 1; and

FIG. 3 is an end elevational view thereof opposite to that shown in FIG. 1.

I claim:

The ornamental design for a locking bicycle stand, as shown.
